UNITED STATES PATENT OFFICE.

HARVEY HUBBELL, OF BRIDGEPORT, CONNECTICUT.

SHADE-HOLDER.

1,135,019.

Specification of Letters Patent. Patented Apr. 13, 1915.

Application filed April 2, 1912. Serial No. 688,078.

To all whom it may concern:

Be it known that I, HARVEY HUBBELL, a citizen of the United States, residing at Bridgeport, in the county of Fairfield and State of Connecticut, have invented certain new and useful Improvements in Shade-Holders, of which the following is a full, clear, and exact specification.

This invention relates to improvements in shade holders, and has particular reference to an improved means for attaching the shade to the support, whereby the shade will be readily attached and detached and at the same time securely held against danger of accidental release of the clamping means which would permit the shade to drop out.

According to this invention, I provide in combination with a support or shell of well-known form a contractible ring which is provided with cam or screw means between its extremities for contracting and expanding the ring to clamp or release the shade, the ring itself having a plurality of points of support in the shell which prevent the ring or any portion thereof from disengaging from the shell or accidentally opening.

In the accompanying drawings, Figure 1 is an elevation of a shade holder embodying the invention; Fig. 2 is a vertical section; and Fig. 3 is a horizontal section taken on the line 3, 3 of Fig. 2.

1 represents the shell or support having a bushing 2 preferably threaded therein, by which the shell is attached to the lamp fixture, and 3 represents the shade, reflector or other device which is to be supported.

4 represents a clamping ring which is resilient, and which is adapted to be contained, when expanded, in the bead 5 of the shell 1. The shell is provided with perforations 6, preferably three in number, disposed substantially equally apart, through which lugs or bent portions 7, 7 of the ring 4 are inserted, and also the ends 8, 8 of the ring, thereby interlocking the ring and shell against vertical movement, or relative rotation. These lugs 7, 7 and the ends 8, 8 sup-

port the ring in the shell, it being seen that the ring carries the weight of the shade. The lugs 7, when bent in the ring, also add resiliency. By means of these different interlocked points of support the shade will be securely held when the ring is properly contracted.

In order to contract the ring, I provide means acting independently of the shell, and preferably carried wholly by the ring, such as a cam or double screw 9, which is threaded through nuts 10, swiveled in the ends 8 of the ring 4 so that the threads will not bind as the ring is contracted or expanded. To clamp the shade, its upper end would be inserted within the ring when expanded, and the ring contracted until the shade is firmly clamped. This permits various sizes of shades to be effectually clamped. It will be seen that accidental disengagement will be avoided, as the ring cannot open by any shock or jar, and, moreover, it is operated by a single clamping device.

Having thus described my invention, I declare that what I claim as new and desire to secure by Letters Patent is:

A shade holder comprising a tubular depending support, formed at its upper end to receive a lamp socket or the like, and enlarged at its lower end to receive the flange of a shade, said lower portion having a plurality of circumferentially extending slots, a shade gripping ring within said support having intermediate projections and its ends extending outwardly through said slots and movable therein to center the ring and shade in the support, and a screw carried by said ring ends outside the support and having opposite threaded engagement therewith for positively expanding and contracting the ring.

In testimony whereof I affix my signature in presence of two witnesses.

HARVEY HUBBELL.
